UNITED STATES PATENT OFFICE.

THOMAS H. LOY, OF BELLAIRE, OHIO.

CONTROLLING MECHANISM FOR SOUND-REPRODUCING MACHINES.

Application filed December 28, 1920. Serial No. 433,709.

To all whom it may concern:

Be it known that I, THOMAS H. LOY, a citizen of the United States, residing at Bellaire, in the county of Belmont and State of Ohio, have invented certain new and useful Improvements in Controlling Mechanism for Sound-Reproducing Machines, of which the following is a specification.

The present invention pertains to improvements in controlling mechanism for sound reproducing machines.

The invention is characterized as to novelty by the provision of means which, speaking with reference to the cycle of their operation and not in the light of their importance, are designed to, firstly, control the co-action of the reproducer with the initial sound grooves of the record; secondly, to control the automatic application of the brake means to the record support in accordance with the termination of the sound grooves; thirdly, to effect repeat movement of the reproducer at the will of the operator in the event repetition is desired; and, lastly, to provide for a subsidiary brake operation under the manual control of the operator at any time during reproduction movement and as an incident to the natural return of the reproducer to substantially record beginning position.

I am aware that it has heretofore been proposed to accomplish certain of the foregoing results, at least, but my aim has been to produce these same ends in a more efficient and satisfactory manner through the instrumentality of mechanism readily adaptable to well known sound reproducing instruments, so coordinating the different controlling units or devices as to greatly facilitate the playing of sound records for various purposes and at the same time enable greater accuracy or positiveness of the sound reproduction, speaking with regard to the application or removal of the stylus in correspondence with the actual sound reproducing portions of the record grooves.

In carrying out these and other objects which will become more apparent as this description proceeds, I contemplate accomplishing the results by mechanism operable either entirely mechanically or electro-mechanically.

For a full understanding of the present invention, reference is to be had to the following description and accompanying drawings in which:

Figure 1 is a top plan view of a sound reproducing mechanism embodying my present invention;

Figure 2 is a bottom plan view, showing more clearly the details of construction of that portion of the mechanism which is supported beneath the supporting plate;

Figure 3 is a view similar to Figure 1 upon an enlarged scale;

Figure 4 is a rear elevation of the reproducer feed and repeat controlling unit or device;

Figure 5 is a detail view in elevation of the levers controlling the elevating and return of the reproducer to the initial or playing position and the co-acting cams therefor;

Figure 6 is a sectional view of the line 6—6 of Figure 4;

Figure 7 is a detailed perspective view of the clutch pawl and releasing arm;

Figure 8 is a side elevation of the reproducer;

Figure 9 is a sectional view taken about 80 on the plane indicated by the line 9—9 of Figure 3; and

Figure 10 is a diagrammatic view of the electric circuit controlling the repeat and brake application operations.

Figure 11 is a detail view of one of the levers for effecting the return of the reproducer, disclosing a means for adjusting the extent of return.

Figure 12 is a fragmentary view on an enlarged scale more clearly showing the attachment for the repeat control device designed to cooperate with the brake mechanism, eliminating necessity for differential adjustment of the record termination indicator.

Figure 13 is a detail view of the attachment referred to in connection with Figure 12.

Figure 14 is a detail sectional view of the circuit breaker somewhat enlarged.

Figure 15 is a modified form of indicator feed worm.

Throughout the following detailed de-

scription, and on the several figures of the drawing, similar parts are referred to by like reference characters.

5 *General construction.*

The present features of the improvements are designed to be applied to a well known type of sound reproducing instrument, the general features of which will be referred 10 to briefly in order to obtain a general understanding of the mechanism with which my invention is designed to co-act. It is to be understood, however, that these improvements may readily be attached to other well 15 known mechanisms and, therefore, I do not desire to be restricted with regard to the modifications that may readily be made within the scope of the invention and the claims hereto appended.

20 Referring to Figures 1 to 3, A represents a suitable supporting plate which is usually mounted upon or within a casing or cabinet from which is supported the motor B operating the drive shaft C from which the 25 driven shaft D is actuated, the latter shaft having mounted fixedly thereon adjacent to an end the worm E with which the segmental rack F engages. This rack is pivotally supported by the bracket G upon a vertical shaft H which is the supporting shaft 30 for the horn and reproducer of this type of sound reproducing mechanism. The shaft H projects through the plate A and carries at its upper extremity the operating handle I provided with a cam J designed to elevate the shaft H and the horn and reproducer carried thereby so as to permit free movement of said reproducer with respect to the record or the turn table upon which the latter is mounted. Upon the spindle C the turn 35 table K is removably disposed and in the usual operation of these machines the sound records, one of which is designated L, are disposed thereupon for reproductive purposes.

40 The tone arm, not shown, in this type of mechanism carries the conventional reproducer M which is provided with a weight or stylus float N having a forwardly extending 45 projection O adapted to cooperate with the supporting loop or ring P when the reproducer arm is elevated to bring the stylus out of cooperative relation with respect to the sound record.

50 Thus far the mechanism described is of conventional form and the operation of the mechanism is well known. It is only necessary, in other words, that the reproducer be moved to a point approximate the first 55 groove of the sound record, whereupon the handle I is elevated to lower the reproducer into playing position, the segmental rack F which is carried by shaft H being simultaneously brought into engagement with the 60 worm E which through the operation of the 65

motor causes the reproducer to traverse the record at a predetermined rate in playing the particular sound record. When the end of the record is reached, it is necessary to manually stop the instrument in the customary 70 manner.

Brake mechanism.

The brake mechanism which is employed in carrying out the present invention follows 75 somewhat closely the type and construction disclosed in my previous Patent No. 1,349,216, dated August 10, 1920. The mechanism consists primarily of the brake member 1 having a shoe 2 at its end which is 80 adapted to cooperate with the rim of the turn table to hold the same against movement in the customary manner. The brake member is provided with a downwardly bent flange 3 operating in an opening 4' of a 85 locking member 4. A spring 5 is connected at one end to the tail piece 6 of the brake member and at its opposite end to the locking member 4 as clearly shown in Figure 3 of the drawing so that the latter element is 90 drawn toward the brake member as an incident of the tension exerted by the spring, while this same tension tends to maintain the brake shoe in contact with the turn table. Beneath and pivotally mounted upon the 95 brake member is a brake setting arm 7 having near its end a notch 8 with which the brake releasing means hereinafter described is adapted to interlock or interengage in the 100 operation of the device. The brake setting arm 7 is provided with an extension 7' from which is upturned a stop 7" engageable with the brake member 4 to limit the movement 105 of the brake setting arm under the actuation of the spring 8'. Fixedly mounted upon the 110 shaft H so as to revolve therewith is arranged the brake releasing means substantially identical in construction with the equivalent part of the mechanism shown in my previous patent above referred to. The 115 plate 9 forming a part of this mechanism is provided with a series of indications 10 with which an indicator or pointer 11 co-acts for the purpose of determining as in my previous patent the point of application of the brake 120 with respect to the termination of the sound reproduction, the rear end of the indicator for this purpose being provided with an extension 12 which is designed to impinge the extremity of the locking lever or member 4 as the release means revolves in the playing 125 operation. The plate 9 furthermore is provided with an arm 13 which is adapted to cooperate with the brake setting arm 7.

Pivots mounted upon the locking mem- 130 ber 4 at 14 is a retaining pawl 15 the hooked extremity 15' of which projects forwardly to a point adjacent to the rectangular opening 4' in the locking lever, said pawl being in a position to engage the brake member 135

when the latter is shifted in the operation of the machine away from the turn table. The pawl is provided with an oppositely extending arm 15" and is placed under tension by the spring 16 so that said pawl will interlock with the depending flange 3 of the brake member when shifted in the manner just referred to.

10 *Record beginning guide.*

Passing now to the special features of the present invention I employ means for positively directing the co-action of the reproducer with the initial part of the record 15 groove so that when the instrument is to be played the reproducer may be deposited in this groove according to the adjustment of the guide means for this purpose. In the type of apparatus which is disclosed in this 20 application it is customary to use sound records which are so manufactured that the sound groove starts substantially always at a particular point in each reproduction. However, in playing the instrument it is 25 necessary for the operator to guess about the point where the groove starts and it is very unsatisfactory to be compelled to shift the reproducer from point to point until the stylus drops into the proper place for the 30 beginning of the sound reproduction. It is quite frequently the case that the stylus is placed upon the smooth portion adjacent to the periphery of the disk and moved by the reproducer feeding mechanism until 35 it arrives at and passes into the sound groove. Ordinarily, however, the sound records must be rotated several times before the sound portion of the grooves is reached. This is unnecessary wear upon the stylus 40 and in some instances the sound given off by the instrument in moving over the groove detracts from the reproduction of the music. With this in view I provide, as above 45 premised, a guide member so that when the latter is properly adjusted for a certain size record the reproducer may be brought to the proper point at all times to begin the reproduction of the music without delay and with great facility. While the specific 50 means for this purpose forms the subject matter of a co-pending application, nevertheless said means will be herein set forth in its cooperative relation to the mechanism involved in this application. Mounted upon 55 the base plate and pivotally secured thereto at 17 I provide a lever 18 formed at one end with a lateral slotted extension 19 through which an adjustment screw 20 extends for the purpose of enabling adjustment 60 of the device. Adjacent this same end of the lever I position a stop pin or guide 21 which is loosely mounted for free movement vertically for reasons hereinafter set forth, said pin projecting downwardly 65 through the base plate sufficiently far to

co-act with the edge of the segmental rack member F when the latter is in its elevated position and the tone arm is free to move arcuately. In other words when it is desired to shift the reproducer inwardly from its outermost position toward the initial groove of the sound record, the reproducer is manually shifted until the edge of the rack member F impinges the pin 21, whereby the operator is advised that the stylus 70 has reached the point for its deposit in the beginning of the sound groove. Thereupon in the natural operation of the instrument the lever I is raised causing the reproducer, as well as the rack member to be lowered, the latter riding along the surface of the pin against which it is held by the operator until the edge of the rack member escapes beneath the lower end of the pin which is just of a proper length to correspond with the point of deposit of the stylus in the sound groove. The rack being now in engagement with its worm the reproducer is 80 free to travel inwardly with respect to the center of the sound record. When the inner end of the sound groove is reached and the reproducer is raised the surface of the rack member F is brought into contact with the lower end of the pin which is likewise elevated by contact with the member F. As 85 the reproducer is brought to its outermost inoperative position the pin will escape the inner end of the rack and thus drop to a position where it will lie in the path of the edge of this rack member to be impinged thereby in a subsequent movement inwardly of the reproducer to playing position. The adjustment which is thus obtained is accurately determinable for beginning the reproduction at the initial portion of the sound 90 record. 95

Repeat mechanism.

The mechanism which has been described above is complete for the single reproduction of sound records, but one of the essential features of the present invention resides

in the provision of means whereby a record or any portion thereof may be repeated one or more times. The uses of repeat mechanism of this character need not be specifically referred to owing to the fact that they are well known at present. Referring to Figures 2 and 7 of the drawings, the shaft D which is driven by means of the gear 24 is provided with a clutch including the spring actuated detent 25 and pawl 26 engageable in the toothed wheel 27. The detent and pawl referred to are mounted upon a shaft 29 in turn carried by the annular collar 30 located at the end of what I term for the purposes of this description the repeat unit. This unit comprises a hollow shaft 31 loosely mounted upon the driven shaft D provided with the cam 32 which is adapted to co-act with the lifting lever 33, a second cam 34 cooperative with an adjacent bell crank lever 35 and the carry over worm or indicator feed means 36. Thus it will be apparent that whenever the pawl 26 is interlocked with the wheel 27, this unit will be operatively connected to revolve with the driving shaft D. Under normal operation of the reproducing instrument, or more strictly speaking, during playing of the record and the traverse of the reproducer thereover, the unit is held relatively stationary by engagement with the detent 25 of a depending arm 37 which, in the construction herein illustrated, is pivotally secured at 38 upon the rear extremity of the latch or locking lever 4 (see Figure 3). Its pivotal mounting, however, is essential only where there is an electrical operation of this part, as later described, independently of the movement of the locking lever, but in its purely mechanical operation the arm 37 may be considered as a relatively immovable part of the lever 4. That it may assume such relation in the operation of the lever, the horizontal portion 38' is bent upwardly at 39 so as to abut against the adjustment screw 40 mounted in a flange 41 on the edge of the lever 4, the part 39 being yieldingly held against its stop by the spring 42.

Reverting now to the co-action of the arm 37 with the detent, the arm's bent extremity stands in front of the detent 25 when functioning to hold the repeat unit in unclutched relation to the shaft D, but a very slight movement of the opposite end of the locking member 4 will transmit sufficient movement to this arm to release the detent, whereupon the unit is clutched to the shaft resulting in rotation of the cams 32, 34, and worm 36. The cam 32 becomes operative first, engaging with the lifting lever 33, which is pivotally mounted upon the depending bracket 43, the opposite end of said lever being engaged with the supporting shaft H so that as the cam depresses

its end of the lever the shaft is elevated in its bearings, thereby raising the reproducer from engagement with the record. Immediately the second cam 34 becomes operative to depress the angle-shaped lever 35 also pivoted on the bracket 43 and arranged to engage the contiguous hook shaped arm 44 of a horizontal operating lever 45 provided with an angle arm 46 adapted to impinge the edge of the bracket G for the segmental rack member F. The moment of its engagement with this element is controlled by the adjusting screw 47 in an obvious manner, and naturally where a different size of record disc is played, this screw 47 may be adjusted to insure the return of the reproducer arm to the proper position for the commencement of the sound groove in such record disc.

Thus the vertical movement of the lever 35 is transmitted into horizontal movement of the lever 45, which in turn brings about the actuation of the reproducer arm in a direction toward the periphery of the record disc. The shape of the cam 34 determines the reverse movement of the reproducer according to the adjustment which has just been mentioned so that it will return said reproducer to the precise point for the stylus to engage in the beginning of the sound groove, or that point in the same where the sound reproduction commences. That is to say, the reproducer will be moved backwardly to a point over the commencement of the groove and at this moment, owing to the shape of the cam 32, the end of the cooperating lever 33 rides off of the same, allowing the shaft H and the reproducer to be lowered so that the stylus drops into the sound groove and the rack F is again in inter-meshing relation with the worm E. This movement to and fro of the reproducer in repetition would continue to the limit of the control of the indicator feed worm 36 but for the interposition of the indicator slide arm 48 which forms a part of the mechanism now to be specifically set forth.

Repeat indicator.

Upon the surface of the support A adjacent to the locking lever 4 is fixedly mounted an indicator plate 49 having thereon indicia designated 50 for indicating the number of times repetition is desired. Pivotally secured to move over this plate is a manually operable adjusting arm 51 having a laterally extending pointer 52 cooperating with the indicia just mentioned. The opposite end of the adjusting member 51 is connected to a slotted slide plate 53 through the instrumentality of the link 54. Guide screws 55 extend through the slots of the plate 54 so as to permit ready movement of this plate under the actuation of the adjusting member 51, and it is

this slide plate which carries the depending arm 48 hereinbefore described.

The arm 48 extends through the support A to a point adjacent the repeat unit and particularly its indicator feed worm 36 with which a finger 56 is adapted to co-act by engagement with the respective spirally arranged ribs or threads 36'.

It will be observed that these ribs, so-called, extend only partway around the worm and the arm 48 is thus capable of movement laterally without interference of the worm whenever the repeat unit is in unclutched or inoperative position. The range of movement of the arm 48 is best shown in Figure 4 and in the dotted line position of said figure the arm occupies such relation to the worm that no repeat action takes place. This corresponds to the position which it assumes when the indicator pointer 52 is moved toward the right to the Figure 1. At such adjustment the record will be played but once and then the mechanism stopped by the brake as will be more fully set forth. The opposite extreme position of the part 56 beyond the last thread or rib, represents such adjustment of the repeat mechanism as will cause the record to be repeated an indefinite number of times. Intermediate positions are capable of being taken by this arm and will determine the number of times the repeat operation is performed, each complete traverse of the reproducer causing a step-by-step movement of the arm toward the dotted line position under the control of the repeat mechanism until the arm 48 arrives at the said dotted line position when it functions to permit of the application of the brake under the control of the release means 9, or more strictly the element 12 thereof.

Mechanical operation.

At this point it is well to obtain a clear understanding of the operation of the mechanism functioning to repeat the playing of a record a plurality of times.

Starting from the beginning the operator takes the desired sound record and places it upon the turn-table in proper position, the tone arm or reproducer being moved over to its inoperative position beyond the edge of the turn-table. The record, as explained in my previous patent herein mentioned, preferably contains an indication thereupon which is designed to indicate the termination of the sound groove of that particular record in accordance with the indicia which is provided for upon the release plate 9. For example, if the record bears the numeral 15, the pointer 11 would, in accordance with my method of the previous patent, be moved to the point 15 upon the indication scale 10. This determines the relation-

ship of the member 12 with respect to the locking lever 4, or the point when these parts co-act to disengage the brake member from its nonbraking position and allow it to cooperate with the turn table. However, in the repeat operation which is to be described, it is obvious that the brake is not to be applied to the record turn-table until the repeat operations desired are complete, so that I arbitrarily set the pointer 11 at a position represented, for example, by two numerals less than 15, in order to insure that the repeat mechanism will become effective. Having positioned the record the reproducer is now moved inwardly, its feed rack F being freed of the feed worm, until such rack impinges the stop pin 21 which immediately advises the operator of the position that the reproducer is to be dropped into contact with the record. It is quite clear that the operator does not require any skill or even any active attention to the position of the reproducer stylus when this stop is employed. Holding the reproducer at the position just mentioned the handle I is raised allowing the shaft H to drop, the reproducer to likewise move, and the rack F to engage with its worm E. During this inward movement of the reproducer the arm 13 is brought into engagement with the brake setting arm 7 in the manner shown in Figure 3 and continued movement toward the depositing position referred to shifts the brake member 1 until it is caught by the pawl 15 which now retains the brake member in the nonbraking position until the end of the repetition. The reproducer feeds across the record toward the axis of rotation under the feeding movement of the rack F and its worm until the termination or approximate termination of the sound groove is reached, at which point the member 12 impinges the end of the locking lever 4 and imparts to the latter preliminary movement. This movement is sufficient to set the repeat mechanism into operation but is insufficient to disengage the pawl 15 from the brake member. In other words, as hereinbefore described, the moment the locking member 4 is moved laterally the depending arm 37 at the opposite end thereof is brought away laterally from the detent 25 which permits the pawl 26 to engage with the wheel 27, thereby locking the repeat unit for rotation with the shaft D.

We will say that at the time of placing the record upon the turn-table it was determined to repeat the record five times, and at such time the adjusting lever 51 was moved to a point where the indicator pointer 52 was on 5. This so positioned the arm 48 that its finger 56 lay at a point to be engaged between the fourth and fifth ribs 36' when the indicator feed worm 36 was rotated by the shaft. This single rotation thereby

110

115

120

125

130

causes the indicator arm 48 to be shifted one step to the right. Reverting now to the interlocking of the repeat unit with the shaft as permitted by the disengagement of the arm 37 from the detent 25, the rotation of the repeat unit as just described also produces the actuations of the lifting lever 33 and its companion lever 35 so that instead of continuing the inward movement the reproducer as well as the release member 9 is caused to return to its initial position or record beginning position. Thereupon the reproducer again moves inwardly for repetition of the record and identically the same action takes place so that the indicator arm 48 is given its second step or increment of movement toward the dotted line position of Figure 4. This continues until the arm is moved to the position shown in such dotted line which is the position corresponding to the adjustment of the indicator pointer to the numeral 1. In the dotted line position the toe extension 48' of the arm 48 lies in a plane in rear of the arm 37 which normally holds the detent 25 in unclutched position. Thus instead of the detent being caught by the arm 37 on this last repeat movement it comes up behind the toe 48' and is held thereby, unclutching the repeat unit from the driven shaft D and permitting the reproducer to move beyond the point of initial actuation of the latch lever 4 by the part 12. This continued movement shifts the lever 4 until the hook or pawl 15 disengages from the brake member 1 allowing the brake member to co-act with the turntable and stop its movement.

The foregoing describes repeat operation of the mechanism and it will be obvious therefrom that the only difference between that and a single reproduction movement lies in the fact that in the latter the indicator 51 is positioned to the extreme right position on numeral 1 where the toe 48' holds the detent, and therefore during the first reproduction the repeat unit is prevented from operating. In other words, as the member 12 comes in contact with the locking lever 4 it causes actuation of the latter until the pawl 15 is disengaged from the brake member. In conclusion, when the member 51 is adjusted for repeat action the toe 48' is drawn away and the detent 25 is allowed to assume cooperative position with relation to the arm 48 as shown in Figure 5, so that on the initial movement of the locking lever the arm 48 is the controlling factor for the repeat operations.

Before passing from this description of the operation, it is desired to set forth two developments of features of the mechanism which are shown in Figures 11 and 12 respectively.

Instead of depending upon the limited range of adjustment of the screw 47 carried

by the lever 46 which returns the reproducer to record beginning position, for purposes of adjustment of the mechanism to enable playing of the different standard sized records, I have devised two adjustable arms 46^a and 46^b pivotally secured to the lever 46 so as to be moved from the inoperative position at one side to a position in advance of the adjusting screw 47, or operative position. Each of these arms is provided with an adjusting screw 47^a so that it is possible to obtain fine adjustments insuring the return of the reproducer to the proper point. In other words, when an 8 inch record, for example, is to be played, the lever 46 and the screw 47 are all that are necessary to return the arm to record beginning position. If a 10 inch record is to be played the operator need only insert his hand into the cabinet and shift the arm 46^a into its position opposite that shown in Figure 11, or if a 12 inch record is to be played the arm 46^a is returned to the full line position of said figure and the arm 46^b shifted into its full line position shown in said figure to take care of proper movement of the reproducer.

Instead of depending upon the adjustment of the indicator pointer 11 in a modified position for repeat purposes as described above, I contemplate eliminating the necessity for so doing by the development or modification shown in Figure 12. To this end the pointer 51 has pivotally connected thereto at an intermediate point the latch bar 57, the opposite end of which is slotted at 58 to engage with the pivot 59 for the brake member 1. This bar is formed with an offset hook shaped arm 60, one edge 61 of which is inclined, said arm 60 being adapted to engage behind the flange 3 of the brake member when the indicator 51 is moved toward the left for any repeat position, such leftward movement causing the brake member to be caught by the arm 60 and drawn from co-action with the pawl 15. In any repeat operation, therefore, the brake member will be held in non-braking position until the indicator 51 is moved to its first position when the brake member will be freed and allowed to engage with the pawl 15 so as to then be under the releasing control of this member as described hereinbefore. With this arrangement when the part 12 impinges the locking lever 4 braking action is immediately produced and simultaneously with the release of the detent by the latch arm 37. The bar 57 is provided with a second arm 62 which is designed to permit the release of the brake at any time during repeat operation when the operator desires to discontinue the playing of the record. This is accomplished by movement of the reproducer toward record beginning position to bring the arm 13 into contact 130

with the arm 62, the continuation of the return movement of which reproducer arm will draw the indicator 51 toward its first position and disengage the arm 60 from the brake lever for application of the brake.

Electromechanical operation.

I have so arranged the mechanism of this invention that it may be either electrically operated or mechanically operated, interchangeably, according to the will of the operator. Each method of operation has its own advantages. For this purpose I position at one side of the locking lever 40 an electromagnet 63 and form the horizontal portion of the member 48 with an upturned flange 64 acting as an armature cooperative with said magnet. This magnet I term the repeat control magnet because it functions for repeat operations only, while I have embodied the second magnet 65 in a position at one side of the tail piece 15' which forms a part of the locking pawl 15, the tail piece being provided 25 with a flange 66 constituting the armature for this magnet. In conjunction with the last named magnet I provide a circuit breaker, consisting of the closely spaced terminals or discs 67 with which a yieldable 30 circuit closer 68 carried by the brake member is adapted to co-act in one position, namely, its non-braking position.

Referring to Figures 8 and 10, and describing the electric circuit, from a suitable 35 source of current 69 a wire 70 leads to the magnet 63 and from said magnet the circuit passes by wire 71 to the contact plate 72 over which the indicator pointer 51 operates. This pointer is provided with a 40 yieldable contact member 73, having a pin 74 passing through a suitable opening in position to ride upon the plate 72 which is provided with depressions 75 representing points of adjustment corresponding to 45 the indications 50. Adjacent to this plate 72, which I call the repeat plate, is a second plate 76, which I call a stop plate, the latter being insulated from the first mentioned plate. The plate 76 is connected 50 electrically by the wire 77 with the lower of the circuit breaker discs 78, while the upper disc 79 is connected by the wire 80 to the brake release magnet 65 also in the circuit from the source of current through 55 the wire 70 and branch wire 81. The source of current 69 on the other side is connected by wire 82 to the reproducer arm at 83, the connection being insulated from the reproducer arm itself but in electrical circuit 60 with the yieldable support 84 for the float N. The supporting loop P of the reproducer is insulated at 85 so that when the projection O is supported by the loop the circuit is open. The reproducer M is 65 grounded as shown at 86, and the yieldable

indicator member 73 is likewise grounded as indicated at 87.

Electrical operation.

In repeat operations where the indicator 70 51 is adjusted to any position other than upon its first position the point 74 is in contact with the repeat plate 72, so that at one side the circuit leads from source 69 through wire 70, magnet 63, wire 71, plate 72, indicator 75 51, by 87 to ground. At the other side from the source 69 through wire 82 to the projection O where the circuit is held open so long as the reproducer is playing and the projection is out of contact with the loop P 80 which is grounded as shown at 86. Immediately the reproducer reaches the end of the record groove and rides upon the smooth portion of the record the float is shifted until the part O comes in electrical contact with the reproducer, immediately energizing the magnet 63 which acts upon the armature 64 and draws the arm 37 laterally to release the detent 25 with the result which has hereinbefore been described of setting the repeat 85 unit into operation and moving the reproducer arm to record beginning position. During elevation and return movement of the reproducer the projection O rests upon the insulation 85 and the circuit is open. 90 This continues to electrically operate in this manner until the indicator pointer 51 is brought to its right-hand position on 1 when the point 74 will stand upon the stop plate 76. The repeat magnet 65 is thus made inoperative and immediately the reproducer reaches the end of the record groove effecting 100 closing of the contact O with the reproducer, the circuit from source 69 passes through wires 70 and 81 to brake release magnet 65, from the latter to circuit breaker 67 through the circuit closer 68 of the brake member, to wire 77 leading to plate 76, through indicator 51 to ground. The closing of the circuit in this manner energizes 105 the magnet 65 which pulls the armature 66 in the direction to actuate the pawl 15 which is withdrawn from engagement with the flange 3 of the brake member and the brake applied. Immediately the brake is in braking 110 position the circuit above described is interrupted by shifting of the closing member 68 away from the circuit breaker 67. 115

It will readily be appreciated from the foregoing that the electrical operation very readily cooperates with the mechanical operation, excepting that the function of releasing the brake member by the part 12 is now dispensed with.

Auxiliary brake arrangement.

One remaining feature remains now to be described which has reference to the provision for manually operating or applying the brake at any time desired during reproduc-

tion operation. For example, if the particular record is not pleasing the operator may cause discontinuance of the playing by elevating the reproducer from the record 5 through the handle 1, shifting the reproducer in reverse direction toward record beginning position which results in the contact of the arm 13 with the brake setting arm 7, which latter arm is formed on the other side 10 of its pivot with an offstanding arm 7^a, the latter arm by continued rotation of the reproducer and movement of the arm 13 being shifted into contact with the tail piece or projection 15^a of the locking pawl 15. Contact between these parts involves obviously 15 disengagement of the pawl 15 from the brake member resulting in the application of the brake.

In Figure 15 I have shown a modified 20 form of indicator feed worm designated 36^x which, instead of being supplied with a plurality of interrupted ribs or threads, is formed with only a single thread the pitch of which is such as to provide for proper co- 25 action with the indicator arm to feed the same step by step.

It should be noted that while I have referred to the element indicated 4 as a locking member and to the part 15' as a locking 30 pawl, I comprehend by the use of the term "latch means" in the specification and claims where it occurs both of these parts broadly, so that where the last mentioned terms occurs it is the unit as a whole that is 35 referred to.

Having thus described my invention, what I claim as new and desire to secure by Letters Patent of the United States, is:

1. In control mechanism for sound reproducing machines having a record support and a reproducer, the combination of a brake member, latch means for holding said member in non-braking position, means operable 40 synchronously with the playing movement of the reproducer into position for actuating the latch means to unlatch said brake member, and means controlled by said latch means for interrupting the unlatching movement aforesaid and reversing the reproducer.

2. In control mechanism for sound reproducing machines having a record support and a reproducer, the combination of a brake member, latch means for holding said brake 55 member in non-braking position, means operable synchronously with the playing movement of the reproducer and adapted to impart initial movement to the latch means, and means set into motion by said initial 60 movement of the latch means to reverse the movement of the brake member unlatching means and thereby prevent setting of the brake.

3. In control mechanism for sound repro-

ducing machines having a record support and a reproducer, the combination of a brake member, latch means for holding said brake member in non-braking position, release means operable during playing movement of the reproducer into preliminary contact with the latch means, and means for returning the reproducer to initial position, said returning means being set into motion by the preliminary contact of the release means as aforesaid whereby complete release of the brake into braking position is prevented.

4. In control mechanism for sound reproducing machines having a record support and a reproducer, the combination of a brake member, a latch means adapted to interlock with the brake member to hold the same in non-braking position, and motor driven means controlled by said latch means and operable at a predetermined point in the traverse of the reproducer in playing for elevating and lowering the reproducer, including means for actuating the reproducer to reverse its traverse between such elevating and lowering movements of the reproducer.

5. In automatic repeat mechanism for sound reproducing machines, the combination with a record support and reproducer, of a brake member, latching means for holding the brake member in non-braking position, mechanism for imparting traverse of the reproducer across the record in playing, and repeat mechanism cooperating with the last named mechanism, including means for elevating the reproducer out of contact with the record and returning the reproducer to record beginning position under the control of the latching means said repeat mechanism rendering the traverse imparting means of the reproducer temporarily inoperative during return movement of the reproducer.

6. In automatic repeat mechanism for sound reproducing machines, the combination with a record support and reproducer, of a brake member, latching means for holding the brake member in non-braking position, mechanism for imparting traverse of the reproducer across the record in playing, and repeat mechanism including means for elevating the reproducer out of contact with the record under the control of the latch means aforesaid and returning the reproducer to record beginning position.

7. In automatic repeat mechanism for sound reproducing machines, the combination with a record support and reproducer, of a brake member, latching means for holding the brake member in non-braking position, mechanism for imparting traverse of the reproducer across the record in playing, and repeat mechanism including means for elevating the reproducer out of contact with

the record under the control of the latch means aforesaid and returning the reproducer to record beginning position and finally lowering the reproducer into contact with the record for repeat movement.

8. In control mechanism for sound reproducing machines having a record support and a reproducer, the combination of a brake member, latch means for holding said member in non-braking position, means operable synchronously with the playing movement of the reproducer into position for actuating the latch means to unlatch said brake member, and means for rendering the holding function of the latch means ineffective at a predetermined time to thereby permit completion of the unlatching movement and application of the brake.

9. In repeat mechanism for sound reproducing machines having a record support and reproducer, the combination of a brake member, latch means for holding said brake member in non-braking position, and means initially cooperative with the latch means to produce repeat operation and subsequently cooperative with latch means to effect braking action.

10. In repeat mechanism for sound reproducing machines having a record support and reproducer, brake mechanism, means for effecting repeat operation of the reproducer, and latch means common to the brake and repeat mechanisms, said latch means being preliminarily operative to permit of repeat operation and subsequent release of the brake mechanism.

11. In repeat mechanism for sound reproducing machines having a record support and reproducer, brake mechanism, means for effecting repeat operation of the reproducer, latch means common to the brake and repeat mechanism, said latch means being preliminarily operative to permit of repeat operation, and means for rendering the latch means ineffective to control the repeat operation.

12. In repeat mechanism for sound reproducing machines having a record support and reproducer, brake mechanism, means for effecting repeat operation of the reproducer, latch means common to the brake and repeat mechanism, said latch means being preliminarily operative to permit of repeat operation, and means for rendering the latch means ineffective to control the repeat operation, said means simultaneously rendering the brake mechanism operative as an incident of the movement of the reproducer in repeat operation.

13. In control mechanism for sound reproducing machines including a record support and reproducer, the combination of a brake member, means for setting said brake member in non-braking position, a latch means

for holding said brake member in said position, motor driven means for effecting traverse of the reproducer across the record, a clutch device, repeat mechanism controlled from said clutch device, means carried by said latch means and cooperative with said clutch device for maintaining the repeat mechanism normally inoperative, and means for actuating the last mentioned means when the reproducer approaches the termination of the record to render the clutch device operative to connect the repeat mechanism with the motor driven means and thereby effect return of the reproducer to record beginning position.

14. Mechanism as claimed in claim 13, wherein the actuating means moves synchronously with the reproducer until it approaches the end of the record and co-acts with the latch means to impart preliminary movement thereto and clutching operation of the clutch device.

15. Mechanism as claimed in claim 13, combined with means adapted to cooperate with the clutch device at a predetermined time whereby the actuating means will operate to shift the latch means and release the brake member for braking operation.

16. Mechanism as claimed in claim 13, wherein the means carried by the latch means comprises an arm arranged to cooperate with the clutch device to hold it in unclutched position, and means operable step by step by the repeat mechanism until interposed between the clutch device and the arm aforesaid whereby the latch means may release the brake for braking operation.

17. In control mechanism for sound reproducing machines including a record support and reproducer, brake mechanism including a latch means for holding the same in non-braking position, repeat mechanism operable when the reproducer approaches the termination of the record, a repeat control device adapted to determine the repeat operations, and means for actuating the latch means upon completion of the repeat operations to permit the brake mechanism to assume braking position.

18. Mechanism as claimed in claim 17, wherein the repeat control device is adapted to be adjusted to determine the repeat operation and is shifted step by step by the repeat mechanism, said device including a part rendering the actuating means for the latch means operative upon completion of the repeat operation.

19. Mechanism as claimed in claim 17, wherein the locking member is provided with a clutch controlling arm shiftable by the actuating means to set the repeat mechanism in operation, and the repeat control device comprises an arm movable upon completion of the repeat operations to assume

the function of the clutch controlling arm aforesaid whereby to permit said actuating means to further shift the latch means and release the brake mechanism for braking 5 operation.

20. Mechanism as claimed in claim 17, wherein the repeat mechanism comprises means controlled through the latch means for raising and lowering the reproducer with 10 respect to the record support and for shifting the reproducer to record beginning position.

21. Mechanism as claimed in claim 17 wherein the repeat mechanism comprises 15 means for raising and lowering the reproducer with respect to the record support and for shifting the reproducer to record beginning position, and separate means for feeding the repeat control device step by 20 step in each repeat operation.

22. In control mechanism for sound reproducing machines including a record support and reproducer, brake mechanism including a brake member, motor driven 25 means for moving the reproducer during playing operation of the record, a latch device for holding the brake member in non-braking position and having a clutch controlling arm, repeat mechanism comprising 30 a unit composed of a clutch device cooperative with the motor driven means and held by the arm aforesaid in unclutched position and a feed element, a repeat control device including an indicator adjustable to determine 35 the repeat operations and means adapted to co-act with the clutch device upon the completion of the repeat operations to prevent cooperation of the arm aforesaid with the clutch device, and means 40 for actuating the latch device when the last mentioned means is in cooperative position with respect to said clutch device to release the brake member to assume braking position.

45. 23. In control mechanism for sound reproducing machines having a motor driven record support and traveling sound reproducer, automatic stop mechanism comprising a brake member, latch means associated 50 therewith including a relatively movable part engageable with the brake member when the latter is shifted to non-braking position; a motor driven rotary part movable to shift the brake member into non-braking position during preliminary movement of the reproducer toward playing position, said rotary part being adapted to co-act with the latch means upon continued 55 operation of the reproducer in playing to shift said relatively movable brake-member-engaging part to release said brake member for braking operation.

60. 24. In control mechanism for sound reproducing machines having a motor driven record support and traveling sound repro-

ducer, automatic stop mechanism comprising a brake member, latch means associated therewith including a relatively movable part engageable with the brake member when the latter is shifted to non-braking 70 position; a motor driven rotary part movable to shift the brake member into non-braking position during preliminary movement of the reproducer toward playing position, said rotary part being adapted to co-act with the latch means upon continued operation of the reproducer in playing to shift said relatively movable brake-member-engaging part to release said brake member for braking operation, a repeat unit adapted 75 to be actuated when the reproducer approaches the termination of the record, said unit comprising means operatively connected to the reproducer to elevate and return the same to record beginning position 80 incident to co-action of the rotary part with the latch means, and a part operable by the latch means when the rotary part aforesaid co-acts therewith to render the repeat unit operative.

25. In control mechanism for sound reproducing machines having a motor driven record support and traveling sound reproducer, automatic stop mechanism comprising a brake member, latch means associated therewith including a relatively movable part engageable with the brake member when the latter is shifted to non-braking position; a motor driven rotary part movable to shift the brake member into non-braking position during preliminary movement of the reproducer toward playing position, said rotary part being adapted to co-act with the latch means upon continued operation of the reproducer in playing to shift said relatively movable brake-member-engaging part to release said brake member for braking operation, a repeat unit adapted 95 to be actuated when the reproducer approaches the termination of the record, said unit comprising means operatively connected to the reproducer to elevate and return the same to record beginning position 100 incident to co-action of the rotary part with the latch means, a part operable by the latch means when the rotary part aforesaid co-acts therewith to render the repeat unit operative and an indicator control device for determining the repeat operations, said indicator device including an adjustable slide 105 and arm adapted to cooperate with the repeat unit aforesaid to be fed thereby in repeat operations into position to prevent the operation of the part actuated by the latch means, whereby the rotary part will impart sufficient movement to the latch means to produce release of the brake member and braking operation.

26. In combination with the sound reproducing machine having a motor driven rec-

- ord support and shaft and traveling sound reproducer, repeat mechanism comprising a repeat unit mounted upon said shaft, said unit being composed of spaced cams and 5 an indicator feed member adapted to be operatively connected for actuation by said shaft, connections intermediate said repeat unit and the reproducer whereby the latter may be shifted from co-action with the record, and indicator means associated with said repeat unit including a part cooperative with the indicator feed member and shiftable step by step thereby to control the repeat operations.
- 15 27. In automatic control for sound reproducing machines, the combination of a brake member, latch means for holding said brake member in non-braking position, a rotary part shiftable during preliminary movement of the reproducer to playing position for setting said brake member in non-braking position, said rotary part being movable to release the brake member upon cooperation with the latch means aforesaid, and 20 means with which said rotary part is adapted to co-act upon movement of the reproducer in the reverse direction to that for playing to disengage said latch means and thereby release the braking member.
- 25 30 28. In automatic stop mechanism for sound reproducing machines, the combination of a brake member, latch means cooperative therewith to hold the brake member in non-braking position, a part connected to the brake member for setting the latter and having means engageable with the latch means to release said brake member, and a rotary part adapted to co-act with said brake member part to shift the brake member into non-braking position upon movement of the rotary part in one direction and to co-act with said brake member part upon movement in the opposite direction to release said brake member from the latch 35 means.
- 40 29. In repeat mechanism for sound reproducing machines including a motor driven record support and traveling sound reproducer, the combination of brake mechanism, repeat mechanism, and a control device including means for effecting repeat operation and separate means for effecting operation of the brake mechanism under the control of the reproducer.
- 45 30. In repeat mechanism for sound reproducing machines including a motor driven record support and traveling sound reproducer, the combination of brake mechanism, repeat mechanism, and a control device including means for effecting repeat operation and separate means for effecting operation of the brake mechanism.
- 50 31. In repeat mechanism for sound reproducing machines including a motor driven record support and traveling sound reproducer, the combination of brake mechanism, repeat mechanism, and a part adjustable with respect to said terminals to control either the repeat mechanism or the brake mechanism according to its co-action with the respective terminals.
- 55 32. In repeat mechanism for sound reproducing machines having a motor driven record support and a traveling sound reproducer, the combination of brake mechanism, repeat mechanism, and control means common to said mechanisms and including an electric circuit, a repeat mechanism terminal in circuit with the repeat mechanism and a separate terminal in circuit with the brake mechanism and circuit closing means movable with relation to said terminals to effect repeat or brake operations according to its adjustment with respect to said terminals.
- 60 33. In automatic control mechanism for sound reproducing machines including a motor driven record support and traveling sound reproducer, the combination of brake mechanism, including an electromagnet, an electric circuit therefor and a circuit closing part, repeat mechanism including an electromagnet, a circuit therefor and a circuit closing part, and means adjustable with respect to said circuit closing parts to determine repeat or brake operations under the control of the reproducer.
- 65 34. In control mechanism for sound reproducing machines having a motor driven record support and traveling sound reproducer, the combination of brake and repeat means, an electric circuit in which both said means are included, said reproducer being also included in the electric circuit, and a circuit closing member for said circuit adjustable to effect closing of the circuit for either repeat or brake operations.
- 70 35. In control mechanism for sound reproducing machines having a motor driven record support and traveling sound reproducer, the combination of brake and repeat means, an electric circuit in which both said means are included, said reproducer being also included in the electric circuit, a circuit closing member for said circuit adjustable to effect closing of the circuit for either repeat or brake operations, and means for normally maintaining the circuit broken when the 75 brake means is in brake-applied position.
- 75 36. In control mechanism for sound reproducing machines having a motor driven record support and traveling sound reproducer, the combination of brake means, an electric circuit in which said brake means is included, said reproducer being also included in the electric circuit, a circuit closing member for said circuit adjustable to effect closing of the circuit for either brake or repeat operations,

and a circuit breaker arranged in the circuit for the brake means and adapted to assume circuit closing position when the brake means is shifted into non-braking position, and to 5 maintain such circuit closed position during repeat operations, said brake means being operable upon movement of the reproducer in its travel over the record support to release the brake means for braking operation, 10 whereby the circuit breaker will be caused to assume circuit broken position.

37. In control mechanism for sound reproducing machines having a motor driven record support and traveling sound reproducer, 15 the combination of brake means including an electromagnet, a brake member, a locking member therefor and an electric circuit, said reproducer being included in said circuit, repeat mechanism including an electromagnet 20 and an electric circuit, a circuit closing member for closing the repeat and brake mechanism circuits in accordance with predetermined adjustment of said circuit closing member, and a circuit breaker arranged in 25 circuit for the brake means and adapted to assume circuit closing position when brake means is shifted into non-braking position, said circuit breaker being operable with the brake means to break the circuit when said 30 braking means is actuated to apply the brake.

38. In control mechanism for sound reproducing machines, the combination with a reproducer member and support, of 35 brake and repeat means operable incident to relative movement between the reproducing member and its said support.

39. In control mechanism for sound reproducing machines, the combination with a reproducer and brake and repeat means, 40 of means movable synchronously with the reproducer, either the brake or repeat means being operable incident to relative movement between the reproducer and said synchronously moving means.

45. 40. In control mechanism for sound reproducing machines, the combination with a reproducer and support therefor, of electrically operated brake and repeat means with which said reproducer is in circuit, 50 said means being operated as an incident to relative movement between the reproducer and its support effecting the closing of the proper circuit of the respective means.

41. In control mechanism for sound reproducing machines, the combination of a 55 movable reproducer member and support therefor, repeat and brake means, of an electric circuit including said repeat means, brake means, the reproducer member and support, the circuit being maintained open while the reproducer member is in playing position, said circuit being closed upon such movement of the reproducer member as is 60 incident to its movement from the sound 65 groove of the record, applying the brake

and rendering the repeat means inoperative.

42. In control mechanism for sound reproducing machines, the combination with a reproducer and support, including a free floating reproducing member, and brake means, of repeat means an electric circuit in which said reproducer, support and free floating member and brake and repeat means are included, the circuit being closed upon relative movement of the free floating member with respect to the reproducer support whereby to set into operation either the repeat or the brake means. 75

43. In control mechanism for sound reproducing machines, the combination of a 80 reproducer, electrically operated brake and repeat means including an electric circuit in which said reproducer is included, and a circuit breaker for maintaining the circuit broken when the brake is in brake applied 85 position, said repeat means including a movable member controlling the operation of the brake means.

44. In control mechanism for sound reproducing machines, a reproducer, brake 90 mechanism, repeat mechanism, an electric circuit including said reproducer, the repeat and brake mechanisms, said circuit being maintained open by the reproducer during playing operations, and a circuit breaker 95 for maintaining the circuit open during non-playing.

45. In control mechanism for sound reproducing machines, the combination of a 100 reproducer, a record support, a brake member for controlling the movement of said support, repeat mechanism, an electric circuit in which said reproducer repeat mechanism and brake member are included, said 105 electric circuit being closed under the control of the reproducer for either brake or repeat operations, and means controlled by the brake member for maintaining the circuit open when the brake is applied.

46. In control mechanism for sound reproducing machines, including a reproducer, the combination with repeat mechanism, of means for predetermining the record-beginning position of the reproducer, said means being maintained inoperative during repeat operations. 110

47. In control mechanism for sound reproducing machines, including a reproducer, the combination with brake and repeat mechanisms, of means for predetermining record beginning position of the reproducer, and means for preventing functioning of the last named means during repeat operations while maintaining the brake mechanism operative upon completion of 115 such repeat operations. 120

48. In control mechanism for sound reproducing machines, including a reproducer, feed mechanism therefor to cause traverse 125 of the reproducer with respect to the record 130

support, of brake mechanism including a 5
brake member automatically shiftable into
non-braking position as an incident to
movement of the reproducer into playing
position, repeat mechanism, and means for
predetermining the record-beginning position
of the reproducer, said means being
maintained inoperative during repeat operations
while the brake mechanism is main- 10
tained operative upon completion of the
repeat operation.

49. In control mechanism for sound re- 15
producing machines, including a reproducer,
feed mechanism therefor to cause traverse
of the reproducer with respect to the record
support, of brake mechanism including a
brake member automatically shiftable into
non-braking position as an incident to 20
movement of the reproducer into playing
position, repeat mechanism, and means for
predetermining the record-beginning position
of the reproducer, and means for pre- 25
venting the functioning of the last named
means during repeat operations while main-
taining the brake mechanism operative upon
completion of such repeat operations.

50. In control mechanism for sound re- 30
producing machines, the combination of a
brake member movable into non-braking
position, repeat mechanism including an ad-

justable member for predetermining the
number of repeat operations, and brake re- 35
taining means connected to said adjustable
member for holding the brake member in
its non-braking position, said brake retain-
ing means being shiftable by the adjustable
repeat member to release the brake for
braking operation.

51. In control mechanism for sound re- 40
producing machines including a reproducer
and a part movable synchronously with the
reproducer, the combination of a brake
member, repeat mechanism including an
adjustable member for predetermining the
number of repeat operations and movable 45
step by step incident to the repeat opera-
tions, a brake-retaining member connected
to said adjustable repeat member and hav-
ing a part adapted to engage and hold the
brake in non-braking position, and a second 50
part with which the first-mentioned part
movable synchronously with the reproducer
is adapted to co-act upon movement of the
reproducer toward record-beginning posi-
tion to effect release of the brake for brak- 55
ing operation and simultaneous normalizing
of the adjustable repeat member.

In testimony whereof I affix my signature.

THOMAS H. LOY.
